UNITED STATES PATENT OFFICE.

CHARLES FRADET, OF ASNIERES, FRANCE, ASSIGNOR TO WALTER SCHINDLER, OF ASNIERES, FRANCE.

LUBRICATION OF PARTS ROTATING AT HIGH SPEED.

Application filed April 20, 1922. Serial No. 555,689.

To all whom it may concern:

Be it known that I, CHARLES FRADET, a citizen of the French Republic, and a resident of Asnieres, Seine, France, have invented new and useful Improvements in the Lubrication of Parts Rotating at High Speed, of which the following is a specification.

This invention relates to means for effecting lubrication of the contacting surfaces of rotary pumps and the like of the radially moving vane type, the vanes being carried by a rotor, and the outer ends of the vanes normally engaging the inner surface of the cylinder or stator. To this end, the invention contemplates the provision of the forward edge of the contacting surface of the respective vanes with a beveled surface, either plain or curved, the angle of the bevel being greater than the maximum angle formed by the normal to the vane and the tangent to the surface of the stator with which the vane contacts, the difference between the angles being such that oil is caused to pass under pressure between the contacting surfaces.

The invention is illustrated in the accompanying drawings, in which:

Fig. 1 is a diagrammatic sectional elevation of a rotary pump involving the invention.

Fig. 2 is an enlarged detail view of the outer end of the vane which engages the stator surface.

Fig. 3 is a similar view showing a modified form of beveled edge of the vane.

Referring to Figs. 1 and 2 of the drawings, *r* indicates the rotor member of the pump, compressor or similar apparatus, in which is mounted the radially movable vane *a*, the outer edge of which engages the cylindrical wall of the stator *d*. The outer and forward edge of the vane *a*, with reference to the direction of movement of the vane, is beveled by cutting away a section represented by the prism defined between the lines *c—c*, *c—g*, and *e—g*, so that the angle α' is greater, for all positions of the rotor, than the angle α , said angle α being that defined between lines *e—n*, which is normal to the longitudinal axis of the vane *a*, and the line *e—i*, which is tangent to the circle defining the wall *d* of the stator at point *e*, and the angle α' being that included between

the normal to the vane *e—n* and line *e—m* defining the beveled surface *e—g*. The angle α is a maximum when the point *e* of the vane engages point *h* of the stator, as indicated in Fig. 1, which point *h* is the intersection of the circumference *d* of the stator and the perpendicular to the middle of line between points *o* and *o'*, which are the centers of the stator and rotor axes, respectively. In other words, the angle α^0 between lines *h—o* and *h—o'* indicates the maximum value of angle α , and in all cases the angle α' must be greater than angle α^0 . The difference of these two angles is such that the oil, which is on the surface of the stator *d*, owing to its inertia, is subjected during the operation of the machine to a pressure forcing it between the contacting surface of the stator *d* and the end of the vane *a*, thus forming a lubricating film which is not scraped off by the rotary movement of the vane. This pressure increases with the speed of the rotor, consequently with the centrifugal force, and balances the latter, and generally all those forces tending to move the vane into engagement with the stator.

Obviously, the plain or prismatic surface *b—e—g* on the outer end of the vane may be replaced by a curved surface, as illustrated in Fig. 3, the generating curve being inscribed in the angle *b—e—g*, the resultant curved and beveled forward edge of the vane serving the same purpose and effect as the plain beveled surface or edge, as indicated in Fig. 2.

What I claim is:

1. Means for effecting lubrication of the contacting surfaces of rotary pumps and the like of the radially moving vane type, which comprises vanes each having the forward edge of its surface engaging the stator wall beveled to an angle greater than the maximum angle formed by the normal to the vane and the tangent to the surface with which the vane contacts, whereby the lubricant is forced under pressure between the surfaces in contact.

2. Means as set forth in claim 1 in which the beveled forward edge of the respective vanes is a curved surface.

In testimony whereof I have signed my name to this specification.

CHARLES FRADET.
